UNITED STATES PATENT OFFICE

104,620

DESIGN FOR A CHIMNEY TOP

Edwin D. Wagner, Akron, Ohio, assignor to The Robinson Clay Product Company, Akron, Ohio, a corporation of Maine

Application March 12, 1937, Serial No. 68,131

Term of patent 14 years

To all whom it may concern:

Be it known that I, Edwin D. Wagner, a citizen of the United States, residing at Akron in the county of Summit and State of Ohio, have invented a new, original, and ornamental Design for a Chimney Top, of which the following is a specification, reference being had to the accompanying drawing, forming a part thereof:

The figure is a perspective view of a chimney top showing my new design.

The other side of the article is like the side shown.

I claim:

The ornamental design for a chimney top as shown and described.

EDWIN D. WAGNER.
